US0D1011479S

(12) **United States Design Patent** (10) Patent No.: **US D1,011,479 S**
(45) Date of Patent: ** Jan. 16, 2024

(54) **WATERING CAN**

(71) Applicant: **Bin Jiang**, Taizhou (CN)

(72) Inventor: **Bin Jiang**, Taizhou (CN)

(**) Term: **15 Years**

(21) Appl. No.: **29/881,000**

(22) Filed: **Jul. 31, 2023**

(51) LOC (14) Cl. **23-01**

(52) U.S. Cl.

USPC **D23/225**; D23/202

(58) **Field of Classification Search**

USPC D23/200, 202, 206, 211, 211.1, 211.2, D23/212, 213, 225

(57) **CLAIM**

The ornamental design for a watering can, as shown and described.

DESCRIPTION

FIG. 1 is a front, right and top perspective view of a watering can, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the watering can that form no part of the claimed design.

1 Claim, 8 Drawing Sheets
